UNITED STATES PATENT OFFICE.

HENRY HAMMAN, OF BURLINGTON, KANSAS.

DESIGN FOR A TUG-HOLDER.

SPECIFICATION forming part of Design No. 26,681, dated February 23, 1897.

Application filed January 2, 1897. Serial No. 617,843. Term of patent 7 years.

To all whom it may concern:

Be it known that I, HENRY HAMMAN, a citizen of the United States, residing at Burlington, in the county of Coffey, State of Kansas, have invented and produced a new and original Design for Tug-Holders, of which the following is a specification.

My invention relates to a new and original design for tug-holders. It relates particularly to the entire configuration of the tug-holder, as illustrated in the accompanying drawing, in which the figure in the drawing is a perspective view of a tug-holder embodying my design.

The leading features of my design appear in the following description:

A represents a cylindrical tapering shank formed with a rectangular transverse yoke B, having forwardly-curved cimeter-shaped parallel arms D D, connected at their outer ends

by a flat bar 2 parallel with the yoke B and at right angles with the tapering shank A. The outer end of the tapering shank A terminates in a cylindrical conical arm M, arranged at a right angle with the shank A and 25 extending in a direction opposite to the curved arms D D and between the plane of the yoke B and the flat bar 2, substantially as shown.

Having thus fully described my invention, what I claim as new and useful, and desire to 30 secure by Letters Patent of the United States, is—

The design for a tug-holder substantially as herein shown and described.

In testimony whereof I have hereto affixed 35 my signature in the presence of two witnesses.

HENRY HAMMAN.
